UNITED STATES PATENT OFFICE.

PERCY H. THOMAS, OF MONTCLAIR, NEW JERSEY, ASSIGNOR, BY MESNE ASSIGNMENTS, TO COOPER HEWITT ELECTRIC COMPANY, OF HOBOKEN, NEW JERSEY, A CORPORATION OF NEW JERSEY.

METHOD OF AND APPARATUS FOR STARTING VAPOR DEVICES.

1,110,591.

Specification of Letters Patent. Patented Sept. 15, 1914.

Application filed December 24, 1906. Serial No. 349,270.

To all whom it may concern:

Be it known that I, PERCY H. THOMAS, a citizen of the United States, and resident of Montclair, county of Essex, State of New Jersey, have invented certain new and useful Improvements in Methods of and Apparatus for Starting Vapor Devices, of which the following is a specification.

My present invention relates to methods and means for starting lamps and other vapor devices, particularly the mercury vapor devices of the Cooper Hewitt type.

The object of the invention is to provide an efficient starting means having certain advantages, among which may be mentioned, freedom from the complications necessarily involved in tilting the lamp whether performed automatically or by hand; and quickness and certainty of operation without sacrifice of any of the advantages appertaining to methods and apparatus heretofore employed by others, as, for instance, to those set forth in the Hewitt and Rogers application, Ser. No. 52,499, filed March 23rd, 1901, and Hewitt application, Ser. No. 211,079, filed June 3rd, 1904.

In the type of devices to which this invention is applicable, the starting operation involves breaking down the negative electrode starting resistance as well as breaking down the nonconducting quality or condition of the vapor column between the main electrodes, and my present invention contemplates establishing an initial current regularly operating between the main negative electrode and a supplemental positive electrode and then transferring the current flow to the main positive electrode, using, if necessary, an accelerated potential to facilitate or insure the transfer. The negative electrode resistance to starting, is overcome by separating current-carrying electrodes within the vacuum in such a manner as to establish current flow through the vapor into the negative electrode so that it no longer has negative electrode resistance to starting. This initial flow of current is established through a supplemental positive electrode preferably normally in contact with the main negative electrode, by passing current initially through a shunt circuit containing a current shifting device. The electrodes are then separated by a comparatively small rel-

ative movement thus establishing current flow through a short column of vapor. The current shifting device may be and preferably is a mercury vapor apparatus having the general characteristics of Cooper Hewitt vapor conductors, but so proportioned and so connected to related circuits including an operating inductance, that when the starting current is thrown through its vapor path, said shifting device is unable to maintain such flow of current continuously, but soon ceases to operate, thereby causing the inductance to develop the accelerated voltage desirable for causing or facilitating current flow between the main operating negative electrode of the lamp or device to be started and the normal or main positive electrode thereof. Other devices for suddenly interrupting flow of current through this path may be employed, but the vapor conductor device is peculiarly adapted for the purpose.

Referring to the drawings, Figures 1, 2, 3, 4, 7, and 8 are diagrammatic views indicating various ways in which my invention may be practised, and Figs. 5 and 6 are details of current shifting devices which may be employed.

The vapor device 1, which may be a lamp used for the purposes of illumination, is suitably supported in any desired position, preferably horizontally or else with the positive electrode 2 located above the level of the main electrode 3, the latter consisting preferably of mercury. The main terminals 4 and 5 are connected with the supply circuit through conductors 6 and 7. The envelop is preferably glass and hermetically sealed after having been cleansed of all foreign gases and gas producing substances.

Adjacent the negative electrode is arranged an auxiliary electrode 8, which is adapted to make and break contact with said negative electrode, the relative movement necessary for this purpose being preferably caused by magnet 9, which may operate to rotate the lamp upon its longitudinal axis, and thus move the mercury in or out of contact with the auxiliary electrode 8, or it may operate directly upon the auxiliary positive electrode within the lamp. In the latter case this electrode 8 will be formed of or provided with magnetic material and adapted for movement to or from the mer-

cury. To this end it may be made of flexible material or wire, or it may be made of comparatively rigid material and formed with a hinge joint connection to the leading conductor 10.

There is a shunt connection 11 from the leading in wire or terminal 4 of the main positive electrode to the terminal 10 of the auxiliary positive electrode 8. This connection contains the resistance 12 of an amount predetermined to suit the conditions, and also the current shifting device 13 of any suitable or desired type.

The current shifting device 13 may be an oil switch or a vacuum break or any type capable of giving sufficiently sharp interruption of current flow. This should be of such a nature as will cause the inductance coil 9 to furnish the desired acceleration of electrical pressure for facilitating or insuring the transfer of current flow from its short vapor path, between the main negative electrode 3 and the supplemental positive electrode 8, to the longer path, between the main negative electrode 3 and the main positive 2.

The movement necessary to open the metallic connection and interpose the vapor path in the shifting device 13 may be imparted either by hand or by the magnet 9 or by a mechanical connection between the vapor device 1 and said shifting device 13, whereby when the former is rotated on its axis the latter will also be moved to open the metallic circuit. As shown in Fig. 1, the shifting device 13 is a device of the Cooper Hewitt type, preferably specially designed and of relative small size, wherein the circuit is made and broken between a solid positive terminal 14 and a negative liquid terminal 15, preferably of mercury.

In the operation of this device, the circuit is closed from the source through the lead 6 and shunt path 11. It flows through the resistance 12; thence through the positive electrode 14 and mercury 15 of the current shifting device 13; thence to auxiliary terminal 10, and through auxiliary electrode 8, main negative electrode 3, and main terminal 5 of the main operating vapor device, and finally through magnet 9 and conductor 7, to the source. The flow of current through this path energizes the magnet 9, thus producing relative movement of main negative electrode 3 and auxiliary positive electrode 8, either by rotating the lamp on its longitudinal axis, or by direct attraction upon the magnetic material of the auxiliary positive electrode 8. The negative electrode 3 starting reluctance of the negative electrode 3, being thus broken down by the flow of current through the short gap between 3 and 8, one of the main factors opposing the starting of the lamp has been eliminated. The flow of current through this path gen-

erates heat and vapor within the envelop, thus modifying the condition of the vapor column between the main electrodes.

The relative movement which causes the starting of the main negative electrode, may be utilized to break the physical metallic contact between the electrodes 15 and 14 of the shifting device. This device has such characteristics of volume, density, heat radiating capacity, etc., that it has an irregularly varying opposition or resistance to the current, and also an irregularly varying critical operating voltage below which it becomes a nonconductor. These irregular variations are particularly marked when the vapor device is cold. The resistances of the circuit, as at 12 and at the negative electrode 3, are such as to limit the energy flowing in the shunt circuit down to values approximating those which are critical to the operation of the lamp. The ordinary "flickering" or abrupt variations characteristic of the phenomena normally observed in the shifting region or point where the current enters the negative electrode, may produce a sufficiently accelerated potential from the reactance to effect starting of the main vapor device. In general, however, the combined resistance including the flickering at the negative electrode of the shifting device, will be sufficient to interrupt completely the current flow therein. In any of the described arrangements, the interruption of the circuit at 13 involves interruption of the circuit at the gap between 3 and 8, and such sudden interruption of flow in the shunt path, causes an acceleration of potential from 9 to impose a breaking down stress upon the nonconducting column between 3 and 2 whereby a flow of current is initiated between them and the device is thus started. It will be obvious that if for any reason the circuit breaks within the lamp at the gap between 3 and 8, the result will be the same.

The shifting device 13 may be connected so that the vaporizable element, such as mercury, is the negative electrode, but, if desired, the connections may be reversed so that the solid electrode is the negative electrode.

If desired, the current shifting device may be operated by a second magnet separate from that used to effect the opening of the circuit between the main negative electrode 3 and the auxiliary positive electrode 8. This is indicated in Fig. 2, wherein the parts are not materially different from those indicated in Fig. 1, except that the mercury electrode and the separation of the electrodes is effected by magnet 9', which is included in a shunt across main terminal 5, and auxiliary terminal 10. It will be obvious that in the operation of this device the magnet 9 effects relative movement and

separation of electrodes 3 and 8 by relative movement thereof, in either of the ways previously described. The increase of resistance due to the interposition of the active 5 negative electrode in place of the physical metallic contact between 3 and 8, will result in an increase of current flow through the shunt path of the magnet 9', thereby energizing the same sufficiently to open the circuit 10 of the current shifting device 13 by bodily tilting the device and thus shifting the mercury terminal 15 after the manner described in connection with Fig. 1.

The starting apparatus may be completely 15 or partially self restoring, as may be found desirable. Where the separation of electrodes 3 and 8 is effected by attraction of magnet 9, operating to draw the latter away from the former, the electrode 8 may be arranged 20 to drop back into contact with the mercury 3 as soon as the magnet 9 is deenergized.

The current shifting device 13 is preferably mounted upon trunnions 16, and may 25 be arranged to remain in the position it is placed so that the metallic contact of electrodes 14 and 15 will remain either closed or open until changed by the operator. In such case the apparatus may be started by 30 positive manual movement of said shifting device to bring the electrodes into and out of contact, said movement being effected by hand of the operator, either applied directly or through suitable intermediate devices. If 35 the device 13 is provided with a self-restoring electrode at 14', Fig. 2, the latter may be arranged to come back into contact with the mercury as soon as the magnet 9' is deenergized. If, however, the magnet 9' is 40 employed to tilt the device 13 by rotary movement about the trunnions 16, a spring 17, or equivalent means, may be employed to effect movement in the opposite direction to restore the contact between 14' and 15. 45 If the magnet 9 is utilized to rotate the entire device about its longitudinal axis to cause separation of electrode 3 and 8 by shifting of the position of the mercury, the restoration may be effected by a spring or 50 equivalent means, and the rotary movement of the device 1 in both directions may be caused to impart suitable corresponding movement to the shifting device 13 through simple link and lever connections. In 55 any case where the connections between the electrodes 3 and 8 of the main device and the electrodes of the shifting device, are made self restoring upon cessation of current flow, the device will be completely self 60 restoring and automatic in its action. If the lamp goes out for any reason, as, for instance, intentional interruption of the circuit thereof or accidental fluctuations of pressure of the supply circuit, the magnet 65 9 and also the magnet 9', if used, will become

deenergized, thereby causing closure of the circuit through electrodes 3 and 8 and electrodes 14 or 14' and 15, thus again placing the apparatus in condition to perform the cycle of operations involved in starting. 70

In the arrangement shown in Fig. 3, the current flows through the shifting device 13 and magnet 9, energizing the latter and thus separating electrodes 3 and 8. At the same time current flows through shunt 75 branch 21 and magnet 22, thereby tilting the shifting device 13 and interposing the vapor path in the circuit thereof. The operation then proceeds as in Fig. 2, except that as soon as the current flows between 80 the main positive 2 and main negative 3, the shunt magnets 9 and 22 may be short circuited and deenergized so that the electrode 8 and shifting device 13 are both automatically restored to normal, closed position, 85 as by the force of gravity against which they must then be raised by the magnets 9 and 22, which is the construction shown. Such immediate, self restoring action at both breaks, closes the shunt circuit around 90 the lamp, and would result in momentarily putting it out of operation and then restoring it. In order to avoid repeated intermittent action of this kind, I may employ an automatic cut-out for the shunt circuit, 95 energized by a coil in the main circuit of the lamp. I have shown such a cut-out arranged in the circuit of Fig. 3, and it will be understood that such device may be applied to the circuits of Figs. 1 and 2. As 100 soon as the lamp starts, the magnet 39 is energized and the entire shunt path is broken, by opening the same at 40, and the lamp continues to operate with the parts thus disposed. If, however, the lamp goes 105 out for any reason, as, for instance, intentional interruption of the circuit thereof or accidental fluctuations of the supply, the automatic switch 40 closes the shunt circuit, again placing the apparatus in condition to 110 perform the cycle of operations first above described. If the conditions causing the lamp to go out are but momentary, it will be automatically restarted at once. If the conditions persist, as where the switch 18 has 115 been opened purposely, the apparatus will be restored to condition for automatically restarting the lamp and such operation will be effected immediately upon closure of the switch. 120

The arrangement shown in Fig. 4 differs from the preceding in certain aspects. It is provided with a cut-out 39 and 40 as in the device of Fig. 3. The device 13' is a vacuum circuit breaker having solid electrodes. The electrode 8' is of flexible material and normally held by its own elasticity out of contact with the liquid electrode, being drawn into contact with the same by the magnet 19, corresponding to magnet 9. Magnets 19 and 130

22 are in parallel with each other, but are connected in shunt across the main negative electrode 3 and the auxiliary positive electrode 8'. The magnet 22 is considerably 5 more sluggish than the magnet 19, so that the vacuum circuit breaker 13' is not tilted to open the circuit until after the magnet 19 has operated. The operation of the magnet 19 is caused by passage of current through 10 the device 13' when in its normal closed position. It draws the electrode 8' into contact with the mercury 3, and being thus short circuited loses its attractive force and the electrode 8' springs back, thus starting current flow between itself and the mercury 3. The circuit of magnet 22 and the winding 15 of said magnet are so designed that said magnet will be able to tilt the device 13', even with the amount of current flowing therethrough after the current has been 20 started through the path between 3 and 8'. The cut-out 39, 40, in this system, as in that of Fig. 3, acts as soon as the lamp is started by flow of current through the main electrodes, the latter resulting from the shock due to break of the shunt circuit through 25 13'. The necessary inductance in this case may be furnished by the magnets 9' and 22, or by a separate coil in conductor 7.

30 It will be understood that the amount of resistance at 12 is predetermined or adjusted with respect to the characteristics of the shifting device 13 to cut down the current flowing through the latter to a point where 35 it will not operate steadily and continuously, but will be in a sensitive, critical state, where the variations of resistance to which I have referred will be sufficient to cause it to lose its conducting quality and thereby interrupt 40 such shunt circuit. In some instances I have noted that the abrupt fluctuations of resistance in the shunt circuit due to the two vapor conducting paths and the unsteadiness at the point where the current 45 leaves the vapor and enters the negative electrode are sufficient to develop an acceleration of potential sufficient to start the lamp without actual interruption of the circuit flow in the shifting device 13. In 50 such case, as soon as the current flows between the main terminals, the resistance through such main path immediately becomes so low as to short circuit the shifting device 13 and thereby cause the vapor gap 55 therein to be restored to the nonconducting condition.

The shifting device 13 operates to produce a very sudden interruption of the shunt circuit at a point outside of the vapor device 60 to be started, and said shifting device 13 need be no larger than is necessary for this purpose. It may be very small in comparison with the size of the vapor device 1, in some instances being not more than a few 65 inches long. Thus it may be very con-

veniently assembled with the other operating parts, in a compact form well adapted for practical use. It is comparatively inexpensive.

It is sometimes desirable to make both 70 electrodes of the shifting device 13 of solid material, in which case the device may take the form shown in Fig. 5, where the vacuated inclosure 41 is formed with trunnions 42 and 43, and provided with a movable 75 electrode 44, hinged to the terminal 45, as shown at 46. Coöperating with this is a relatively fixed electrode 47, extending transversely of the path of movement of said movable electrode 44, and connected to the 80 other terminal 48.

In Fig. 6 I have shown a current shifting device having both operating terminals of liquid material, preferably mercury. The device consists of a glass case 53 provided with trunnions 54 and 55, and formed with two depressions or cavities 56 and 57, separated by the ridge 58 serving the function of a partition to separate the two bodies of liquid. From points diametrically opposite 90 each of said depressions, the walls of the vessel are carried in diametrically across the same into a point near the bottom of said receptacles 56 and 57. Conductors 59 are connected to leading in wires 60, sealed into 95 the ends of the same, and coming into contact with the liquid mercury. In operation of the device to make and break the circuit, it is rotated about the trunnions 54 and 55 as an axis, thereby causing the mercury to 100 bridge across one end of the elevation or partition 58 and upon a reverse movement, the bodies of mercury are separated. If the current is impressed on the conductors 59 and 59 at this time, it will be made and 105 broken by this rocking movement.

In Figs. 7 and 8 I have shown a concrete form of a modification of my invention, which has many practical advantages of construction and of operation, both mechanical and electrical. In this device the separation of the main negative electrode and the supplemental positive starting electrode is effected by rotation of the lamp about its longitudinal axis, thereby causing the mercury of the negative electrode to flow into and out of contact with the supplemental positive electrode. As shown, these electrodes are adapted to be normally in contact and to be moved out of contact. During the 110 operation of the device, they are preferably normally held out of contact. The vapor electric device in this case is used as a lamp, and is shown in a horizontal position. This 115 position is very desirable where the lamp is used for light giving purposes, and has been discovered by us to be practicable where the lamp is provided with a condensing chamber adjacent the negative electrode as shown. The positive electrode seems to maintain a 120 125 130

high temperature in the remote portions of the tube, so that practically all condensation is determined in said condensing chamber, where it falls directly back into the body of 5 mercury constituting the main negative electrode. In said figures the apparatus is mounted in a suitable support, comprising a chamber 30, suspended by pipe 31, and in closing the auxiliary parts of the apparatus. 10 Extending from said chamber are tubular supports 32, 33 terminating in depending suspension devices 34 and 37. The latter terminate respectively in straps or openings 35, 38, movably but securely engaging extensions 36, 39, said extensions being preferably made integral with the lamp tube. The auxiliary operating mechanism is contained in the chamber 30, and comprises a ballast 40 of any ordinary or desired type, a resistance 15 12^a, an operating electromagnet 9^a, and a current shifting device 13^a, said parts being connected up and operating in a manner hereinafter described. The lamp being rotatably mounted, as described, is preferably 20 normally in the position shown in Fig. 8, with the supplemental positive electrode in contact with the mercury, the separation being caused by movement about the longitudinal axis of the lamp to the position 25 shown in Fig. 7. The ballast 40 is arranged in series with the lead to the positive electrode 2^a, from which the circuit, during the normal operation of the lamp, is completed through the main vapor column 30 35 1^a, negative electrode 3^a, and negative lead 7^a. In the main negative lead is serially arranged the operating electromagnet 9^a, which performs several functions. It serves as a starting inductance for furnishing the 40 accelerated potential for effecting the transfer of the path of current flow from the supplemental positive electrode path to the main positive electrode path; also as a steadyinductance to prevent unsteadiness of operation of the lamp, and, finally, as a source of power for effecting the necessary mechanical movement of the movable parts, through movement of the armature 41. The movement of the armature 41 serves 45 to rotate the lamp about its longitudinal axis to separate the starting electrodes and also to rotate the current shifting device 13^a to separate the electrodes thereof. The movement of the armature is applied to effect 50 this purpose by any desired mechanism, as for instance, by a link 42, connected to a lever 43, pivoted at 44, and connected by link 45, with lever arm 46, secured to the lamp by ring 47, encircling the same. The 55 lever 43 is also pivotally connected to link 48, which is in turn pivoted to an arm 49 extending from the current shifting device 13^a. The device 13^a may be of any of those 60 previously described, but, as shown in the drawing, is of the form illustrated in Figs. 65 4 and 5. It is connected in a shunt circuit leading across the main positive to the main negative through a resistance 12^a, similar to the resistance 12, previously described, and through the supplemental positive electrode 8^a and the main negative electrode 3^a to line. With the parts in the position shown in Fig. 8, the armature 41 is in its lowermost position, and the shunt circuit is closed through 13^a, 8^a, and 3^a. When current is 70 turned on, it flows through this shunt path and energizes the magnet 9^a, which attracts the armature 41, thereby rotating the lamp to the position shown in Fig. 7, thus causing an initial flow of current from the auxiliary 80 positive 8^a into the main negative electrode 3^a. It also rotates the current shifting device 13^a, the relation of parts being such that the circuit is broken in 13^a after 8^a and 3^a have been separated and current flow 85 from the former into the latter has been initiated. The flow of current into 3^a breaks down the negative electrode reluctance to starting, and subsequent separation of the electrodes of 13^a, causes an accelerated potential developed in the winding 9^a, to be 90 impressed upon the main electrodes of the lamp, thereby causing a breaking down stress and consequent flow of current from the main positive electrode 2^a through the 95 main vapor column of the lamp to the main negative electrode 3^a. The electromagnet 9^a, being in series with the main negative lead, remains energized during the operation of the lamp and serves to maintain the parts 100 in the position described, as long as current flows between the main electrodes of the lamp. The weight of the armature, assisted by a spring or other auxiliary means, serves to restore the parts to the initial position 105 shown in Fig. 8 as soon as current ceases to flow and said magnet 9^a is deenergized. 110 It will be understood that the practical outfit described above may be modified so as to embody any of the principles of operation hereinbefore described with respect to Figs. 1, 2, 3, 4, and 6 of the drawings. 115 In all arrangements shown herein, the arrangement of parts may be such that separation of the main negative electrode and the supplemental positive electrode within the lamp, takes place either before or after the separation of the electrodes in the current shifting device. It will be found in practice, however, that where a solid negative electrode is used in the current shifting device, as in Fig. 5, it is preferable to have the separation occur within the lamp before the electrodes of the shifting device are separated, because the solid negative electrode is 120 not so well adapted to sustain a considerable current for any length of time. If the negative electrode of the shifting device is of mercury, or if both of the electrodes of the shifting device are of mercury, as, for in- 125 130

stance, in the device of Fig. 6, it will be found practicable, and sometimes even preferable, to cause the separation of the electrodes in the shifting device to precede the separation of the main negative electrode and the supplemental positive electrode within the main lamp.

I claim as my invention:

1. An electrical translating device, adapted to operate on a current of known potential and requiring an initial current of relatively higher potential for starting, in combination with an inductance and an unstable, vapor electric device, adapted to vary and interrupt a flow of current in said inductance and thereby supplying the higher potential.

2. An electrical translating device adapted to operate on a current of known potential and requiring an initial current of relatively higher potential for starting, and a reactance device in series therewith, in combination with a self-restoring current shifting device in shunt to said translating device, constructed and arranged for unstable, discontinuous operation, thereby to interrupt said shunt circuit and to develop in said reactance device a higher potential for starting said translating device.

3. A vapor electric apparatus and a reactance in series therewith, in combination with a second vapor electric apparatus in series with said reactance, and in parallel to said first named apparatus, together with a resistance for rendering unstable the operation of said second vapor electric apparatus.

4. A vapor electric apparatus comprising an inclosure, main electrodes, and a supplemental positive electrode, and a reactance in series therewith, in combination with a second vapor electric apparatus in series with said reactance and supplemental positive, and in parallel to said first named apparatus, together with a resistance for rendering unstable the operation of said second vapor electric apparatus.

5. A vapor electric apparatus and a reactance in series therewith, in combination with a second vapor electric apparatus in parallel to said first named apparatus and in series with said reactance device, together with means for rendering unstable the operation of said second vapor electric apparatus.

6. A plurality of vapor electric devices, a common reactance in series with said vapor devices, one of said vapor electric devices being constructed and designed for variable or discontinuous operation.

7. A plurality of vapor electric devices, a common reactance in series with said vapor devices, one of said vapor electric devices being of small size constructed and designed for unstable, discontinuous operation.

8. A vapor electric device and a reactance

in series therewith, in combination with a second vapor device of smaller size forming part of the system and constructed and arranged for unstable, discontinuous operation, whereby the flow of current in said second vapor device will be interrupted and a starting current developed for initiating the flow of current through the other device.

9. An electrical translating device requiring an initial current of relatively high potential for starting, and a reactance device in series therewith, in combination with a quick-break device for supplying the higher potential, such quick break device being itself an unstable, vapor electric apparatus of comparatively small size.

10. A vapor electric device of the class described and a reactance in series therewith, in combination with a shunt circuit upon the vapor device, said shunt circuit including a second vapor device of small size adapted and arranged for unstable, discontinuous operation, whereby upon interruption of the circuit in said second vapor device, a high potential current adapted to start said first mentioned vapor electric device will be set up by said reactance device.

11. A device adapted to operate on a known potential and requiring a starting current of relatively high potential and an inductance in operative relation to said device, in combination with a switch located in shunt upon said vapor device, the said switch being itself a vapor device of small size designed and arranged for unstable, discontinuous operation.

12. In a vapor electric apparatus of the class described, a supply circuit, an inclosing chamber, suitable electrodes within said chamber, and a body of gas or vapor between said electrodes, in combination with a starting apparatus therefor comprising a shunt circuit, containing a resistance and a vapor conducting device, designed and arranged to become nonconductive and thereby to interrupt said shunt circuit, together with means whereby gravity will restore said vapor device to condition for restarting and an automatic switch operating to open said shunt circuit when current flows through said first mentioned device.

13. A vapor electric device of the class described, having main electrodes and a movable supplemental positive electrode adjacent a main negative electrode and normally contacting therewith; and a coil in series with both said main electrodes for separating said supplemental electrode and main negative electrode, in combination with a circuit in shunt around the other main electrode and a portion of the vapor column of said device, but in series with said supplemental electrode, adjacent main electrode and coil; and a switch in said shunt circuit.

14. A vapor electric device of the class

described, having main electrodes and a supplemental electrode adjacent a main electrode; a main circuit for said main electrodes, and a coil in said circuit, in combination with a circuit in shunt around a main electrode and a portion of the vapor column of said device, but in series with said supplemental electrode, with said adjacent main electrode and coil; and a switch in said shunt circuit.

15. A vapor electric device of the class described, having main electrodes and a supplemental electrode adjacent a main electrode; a main circuit for said main electrodes, and a coil in said circuit, in combination with a circuit in shunt around a main electrode and a portion of the vapor column of said device, but in series with said supplemental electrode, with said adjacent main electrode and said coil; and a switch in said shunt circuit operating to open said shunt circuit automatically whenever current flows therein.

16. A vapor electric device of the class described, having main electrodes one being a negative electrode and a movable supplemental positive electrode adjacent said main negative electrode and normally contacting therewith, and a coil in series with both said main electrodes for separating said supplemental electrode and main negative electrode, in combination with a circuit in shunt around a main positive electrode and a portion of the vapor column of said device, but in series with said supplemental electrode, with said adjacent main negative electrode and said coil; and a switch in said shunt circuit operating to open said shunt circuit automatically whenever current flows.

17. A vapor electric device of the class described, having main electrodes one being a negative electrode and a movable supplemental positive electrode adjacent said main negative electrode and normally contacting therewith; and a coil in series with both said main electrodes for separating said supplemental electrode and main negative electrode, in combination with a circuit in shunt around a main positive electrode and a portion of the vapor column of said device, but in series with said supplemental electrode, with said adjacent main electrode and said coil, and a switch operating to open said shunt circuit automatically whenever current flows.

18. A vapor electric device of the class described, having main electrodes one being a negative electrode and a movable supplemental positive electrode adjacent said main negative electrode and normally contacting therewith; and a coil in series with both said main electrodes for separating said supplemental electrode and main negative electrode, in combination with a circuit in shunt

around a main positive electrode and a portion of the vapor column of said device, but in series with said supplemental electrode, with said adjacent main negative electrode and said coil; and a second vapor device in said shunt circuit operating to open the same automatically whenever current flows therein.

19. A vapor electric device of the class described, having main electrodes and supplemental means for impairing the electrode reluctance to starting at the negative electrode, a main circuit and a coil in said circuit, in combination with a circuit in shunt around a main electrode and a portion of the main vapor path through said device, but in series with said coil; and a second vapor device interposed in said shunt circuit, normally closing, but operating to open said shunt circuit automatically when current flows therein.

20. A vapor electric apparatus of the class described, having a supplemental positive electrode, means for moving said electrode into and out of contact with the negative electrode, and a circuit for said means, in combination with a self-restoring circuit breaker in said circuit and an automatic cut-out operating to open said circuit when said first mentioned vapor device is in operation.

21. A vapor electric device and means for starting the same, including a shunt circuit, current shifting device, and a supplemental positive electrode for impairing the negative electrode reluctance to starting, in combination with an electromagnet in series with said vapor device and with said shunt circuit, said electromagnet being designed and connected to serve as a starting inductance for starting the lamp, as a steadyinductance for keeping it alive when started, and as a motor for effecting the necessary movement of the movable parts.

22. A vapor electric device and means for starting the same, including a shunt circuit, current shifting device, and a supplemental positive electrode adjacent a main negative electrode for breaking down the negative electrode reluctance to starting, in combination with an electromagnet in series with said vapor device and with said shunt circuit, said electromagnet being designed and connected to furnish the necessary inductance for starting the lamp and for keeping it alive when started; and to serve as a motor for relatively moving the supplemental and main negative starting electrode.

23. A vapor electric device and means for starting the same, including a shunt circuit, current shifting device, and a supplemental positive electrode adjacent a main negative electrode for breaking down the negative electrode reluctance to starting, in combination with an electromagnet in series with

said vapor device and with said shunt circuit, said electromagnet being designed and connected to furnish the necessary inductance for starting the lamp and for keeping it alive when started; and to serve as a motor for relatively moving the supplemental and main negative starting electrodes and for moving said circuit shifting device.

24. In an electric lighting apparatus, a vapor electric lamp comprising an elongated glass tube, formed with a cavity containing liquid mercury, and with an enlarged condensing chamber adjacent the latter, a supplemental positive electrode normally in contact with said mercury, a main positive electrode at the remote end of the tube, said lamp being also provided with trunnions for movement thereof about its longitudinal axis to separate said mercury electrode from said supplemental positive electrode; a support for said lamp adapted to maintain the same in a substantially horizontal position, such support comprising a chamber inclosing the auxiliary apparatus for operating the lamp and members engaging the axial trunnions at the ends of the lamp, and supporting said lamp in substantially horizontal position, in combination with the operating circuits and mechanism for said lamp, comprising positive and negative leads passing through said inclosing chamber to the main leading in

conductors of the lamp, and having serially interposed therein a ballast and an electromagnet in operative relation to an armature mechanically connected to rotate the lamp about its longitudinal axis, to cause the mercury electrode to flow out of contact with the supplemental positive electrode; a shunt circuit across the main leads of said circuit, said shunt circuit having serially included therein a resistance and a current shifting device mounted for movement, said shunt circuit being completed through the supplemental positive electrode to the main negative electrode of the lamp; and interdependent connections whereby the axial movement of the lamp involves movement of the current shifting device to separate the electrodes thereof; said electromagnet being designed to have inductance, operating to serve as starting inductance for effecting transfer of current flow from the supplemental starting path to the main vapor path of the lamp, and also to serve as steadyng inductance while the lamp is in operation.

Signed at New York in the county of New York and State of New York this 19th day of December, A. D., 1906.
